LIQUID DELIVERY OR SUPPLY APPARATUS

Albert Thomas Juniper, Liverpool, England

Application January 19, 1955, Serial No. 482,860

2 Claims. (Cl. 222—158)

This invention relates to the delivery or supply of liquid (for example oil) under pressure, more particularly to receptacles—such, for instance, as oil tanks of aircraft—which, or the inlet orifices whereof, are difficult of access for filling and replenishment or “topping-up,” as and when required; and the invention has for its object to provide apparatus, including a delivery unit or “gun,” adapted for the supplying to a tank of predetermined quantities of liquids; said unit or gun including a graduated container whereinto liquid from said tank can be filled, and wherefrom liquid may be dispensed, via a nozzle of said unit or gun, by means of compressed air admitted to said container. The unit or gun includes a two-way valve for selectively connecting same with the liquid of said tank and with the compressed air thereof, and also a valve for admitting said liquid or compressed air, according to the position of said two-way valve, to the graduated container. Said second-mentioned valve is spring-urged to closed position and is hand-operable by means of a trigger-lever.

In use, said two-way valve is connected by flexible twin piping to the tank, which may be of any suitable type, containing under air pressure the liquid to be dispensed, one of the flexible pipes being in communication with the compressed air of the tank and the other pipe with the liquid. Thus, on appropriate positioning of the two-way valve, and opening of the trigger-valve, oil will be fed into the graduated container to required level by the air pressure in the tank, and, on reversing said valve, compressed air from the tank may be introduced to said container to discharge its contents, or a portion of same, via the nozzle of the gun.

I will further describe my invention by the aid of the accompanying explanatory drawings, which illustrate, by way of example only, and not of limitation, one mode of embodiment.

In said drawings:

Fig. 1 is a side elevation of a liquid delivery gun under the invention.

Fig. 2 is a section taken as on line II—II, Fig. 3.

Fig. 3 is a plan view, and

Fig. 4 is a fragmentary view, drawn to an enlarged scale as compared with the preceding views, showing part of Fig. 2.

Referring now to said drawings, 10 denotes a cylindrical barrel one end whereof is internally screw-threaded, as at 11, and fitted to a block 12 having an externally screw-threaded part 13 which is provided with a valve opening 14 (Fig. 4) the latter communicating with a longitudinal passageway 15.

An aperture 16 drilled laterally from the underside of block 12 opens into passage 15 and is screw-threaded to receive a tube 17 which passes through an aperture provided in a circular plate 18 mounted on the underside of block 12 by means of a screw 19. Block 12 is also formed with a longitudinal passage 20 communicating with a lateral passage 21 which is screw-threaded to receive

2

a tube 22 also passing through plate 18; a gasket (not shown) is fitted between block 12 and plate 18 to provide an air-tight seal, and tubes 17 and 22, are, respectively, provided with flanges 17^a and 22^a between which

5 and the under surface of plate 18 are disposed washers 23, 24. A washer 25 is fitted on screw 19.

Spacedly connected to plate 18 by means of tie-rods 26 with draw-up nuts 26^a is a circular plate 27, and between said plates is clamped a transparent or partially 10 transparent graduated cylindrical container or jar 28 which has its lower closed end 28^a located in a correspondingly shaped recess 27^a of plate 27, and its upper rim 28^b seated in air-tight manner against a ring 29 of rubber, or other suitable resilient substance, inset into the underside of plate 18. Tubes 17 and 22 thus open within and are enclosed by container 28. A vent valve 30 with a tap 30^a is mounted on plate 18 in order that the container 28 may be opened to the atmosphere as and when required.

Disposed within barrel 10 is a longitudinally displaceable rod 31 having mounted on its forward end a valve

20 closure 32 of circular cross section, which is a sliding fit within valve-opening 14 of block 12 and is provided with a series of longitudinally disposed channels or flutings 32^a. Rearwardly of flutings 32^a of valve closure 32 is formed a flange 32^b with a washer 32^c which is adapted to form an oil-tight and air-tight seal when seated against the rim 14^a of valve opening 14. The end of rod 31 remote from valve 32 is screw-threaded as at 31^a, and projects from barrel 10 through a gland 33 located between an internal flange 10^a of barrel 10 and a gland nut 34. Disposed around rod 31, being confined between said flange 10^a and a flange 31^b of rod 31, is a helical compression-spring 35 which continuously urges valve 32 to closed position, as shown in Fig. 2.

35 The end 31^a of rod 31 is threaded through an aperture of a stirrup 36 and fitted with stop nut 37, the free ends of said stirrup being pivotally connected by nuts and bolts 36^a to the arms 38^a of a bifurcated trigger-lever 38 which, in turn, is pivoted by screws 39 to a bridge piece 40 provided on barrel 10. It will thus be seen that if pressure

40 is applied to trigger-lever 38 in the direction of the arrow (Fig. 1), rod 31 will be moved rearwardly against the influence of spring 35 by stirrup 36, and the flange of valve 32 will become unseated from the rim 14^a of valve opening 14, as shown in Fig. 4.

45 Communicating with the bore of barrel 10 is a rigid pipe 42 which is secured in position by way of a block 41 welded or brazed to said barrel, and the end of pipe 42 is screw-threaded to receive the end 43^a of a two-way valve, generally designated 43, provided with branch pipes 43^b and 43^c. Said valve 43 may be of any suitable kind, and in this instance includes a turn-key or tap 43^d whose movement is limited by two stops 43^e, 43^f. In the stop position shown in Fig. 1, branch 43^b is closed and branch 43^c is connected with pipe 42. In the other stop position branch 43^c is closed and branch 43^b is connected with pipe 42.

50 The discharge nozzle of the gun may be of any type appropriate to the purpose for which it is to be used, and as shown in the drawings, a length of flexible hose 44, having nozzle-ends 45 with union nuts 46, is mounted on the forward end of block 12 which is turned to circular cross-section and screw-threaded as at 47 to receive same.

55 In using the gun, one of the branch pipes of valve 43, for example branch 43^b, is connected by flexible piping to a supply of liquid contained in a tank (not shown) under air pressure, and the other branch 43^c is similarly connected with a source of compressed air, conveniently that of the liquid supply tank. The transparent container 28 may then be charged with liquid (a) by manipulating valve 43 to connect branch 43^b to pipe 42,

(b) opening vent valve 30 to atmosphere, and (c) pressing trigger-lever 38, when liquid will be forced through pipe 42 into the bore of barrel 10 through the valve opening 14, via the flutings 32^a of valve 32, and thence, by way of passages 15, 16 and tube 17, to container 28. The amount of liquid introduced to container 28 can be accurately controlled by timed release of trigger-lever 38, having due regard to the graduations marked on the container.

To discharge the contents of container 28, the setting of the two valves 30 and 43 is reversed, i. e. valve 30 is closed and branch 43^c opened to pipe 42. When trigger-lever 38 is now operated, container 28 will become pressurised and its contents discharge via tube 22, lateral passage 21, passage 20, and so through flexible hose 44.

For comfort of handling, a suitably shaped handle component 48 is fitted over tube 42 and secured in position against blocks 43 by means of a clamp nut 49.

What I claim as my invention and desire to secure by Letters Patent is:

1. Apparatus for the delivery of measured quantities of liquid, comprising a graduated container, a first tube, a second tube and said first tube extending into said graduated container, a cylindrical barrel attached to said

container, a two-way valve connected to said barrel and the bore thereof for selectively connecting the bore of said barrel with a liquid under pressure from a supply tank for a supply of compressed air, a normally closed trigger-operable valve controlling the flow between the bore of said barrel and said first tube whereby liquid or compressed air according to the position of the two-way valve can be supplied to said container, and a nozzle having said second tube connected thereto whereby liquid from said container may be discharged by means of compressed air admitted to said container via said first tube.

2. Apparatus for the delivery of measured quantities of liquid according to claim 1, wherein a vent valve is provided for at times opening said container to the atmosphere, a handle is connected to said barrel and said two-way valve is positioned at said handle.
